UNITED STATES PATENT OFFICE.

THOMAS J. CARSON, ROSWELL H. WILLIAMS, AND DE WITT C. TURNER, OF GREENFIELD, MISSOURI; SAID WILLIAMS AND TURNER ASSIGNORS TO SAID CARSON.

REMEDY FOR RHEUMATISM, &c.

SPECIFICATION forming part of Letters Patent No. 367,337, dated July 26, 1887.

Application filed March 24, 1887. Serial No. 233,312. (No specimens.)

To all whom it may concern:

Be it known that we, THOMAS J. CARSON, ROSWELL H. WILLIAMS, and DE WITT C. TURNER, citizens of the United States, residing at 5 Greenfield, in the county of Dade and State of Missouri, have invented certain new and useful Improvements in a Medical Compound for Treating Rheumatism; and we do declare the following to be a full, clear, and exact description of the invention, such as will enable others skilled in the art to which it appertains to make and use the same.

The object of our invention is to provide a compound for treatment of rheumatism, acute 15 colic, sprains, earache, indigestion, or for alleviating pain; and to this end our invention consists in a mixture of the following ingredients, namely: pond-lily, (Nymphaea), black cohosh, (Cimicifuga), silk-weed, (Asclepias 5,) 20 alcohol, and pure water. These are compounded or united in the following manner and proportion: pond-lily, two ounces; black cohosh, two drams; silk-weed, one dram; alcohol, half-pint. Add pure water to make one 25 quart.

In compounding the above mixture, we use only the tincture of each—that is to say, the tincture of pond-lily, black cohosh, and silk-weed. The alcohol is used in the common 30 form, except that it is always understood that it shall be of "high proof." We prefer to use pure filtered soft water free from any lime deposit or other foreign substances.

In preparing the compound, all of the ingredients (except the water) are carefully measured, then all united, and the water added, when the whole is thoroughly agitated, after which it is put into the proper-sized bottles and labeled, when it is ready for use.

All of the ingredients used are safe and 40 valuable, possessing remedial properties of a high order, and they are combined in a safe and judicious manner, so as to bring into operation the valuable powers of all the elements.

Our compound is to be used, preferably, as 45 an external remedy by rubbing upon the afflicted parts, or by saturating a cloth with the mixture and binding on, as on rheumatic joints. When used as an internal remedy for rheumatism, acute colic, or cramps, one table-spoonful is to be taken at each dose until relief is obtained. In cases of toothache, ear-ache, and sprains, it can be applied with perfect safety and with the certainty of securing prompt relief. 55

Having described our invention, what we claim, and desire to secure by Letters Patent, is—

A medical compound composed of the tincture of pond-lily, two (2) ounces; tincture of 60 black cohosh, two (2) drams; tincture of silk-weed, one (1) dram; alcohol, half ($\frac{1}{2}$) pint, and pure water, to make one (1) quart in all, substantially as set forth.

In testimony whereof we affix our signatures 65 in presence of two witnesses.

THOMAS J. CARSON.

ROSWELL H. WILLIAMS.

DE WITT C. TURNER.
